CORE BARREL

Original Filed March 17, 1924

EDWARD F. RAYMOND,

INVENTOR

By Oliver S. Barnum

ATTORNEY

UNITED STATES PATENT OFFICE.

EDWARD F. RAYMOND, OF SANTA FE SPRINGS, CALIFORNIA, ASSIGNOR TO REED AND WILLIAMS ENGINEERING COMPANY, OF LOS ANGELES, CALIFORNIA, A CORPORATION OF CALIFORNIA.

CORE BARREL.

Application filed March 17, 1924, Serial No. 699,783. Renewed September 22, 1925.

My invention pertains to a core barrel adapted to drill and preserve a core to show the formation of geological strata through which the tool travels. The objects are to provide a core barrel which may be easily and quickly dis-assembled to allow the core to be removed intact; to make such a core barrel that may be reasonably cheap to manufacture; durable, and with a minimum of danger of the same being lost in the hole.

I attain these objects among others by the provision, construction and assembling of the various members and parts shown in the accompanying drawings, in which

15 Figure 1 is a view of the essential parts of the core barrel in apposition for rigid assembling.

Figure 2 is a view of the lower or drilling end of the core barrel, looking in the direction of arrow A.

Figure 3 is a view of the core bit, in separable halves.

Figure 4 is a cross-sectional view of one half of the core barrel, showing in particular the relation of drilling bits and core bit, and a spiral rifling of the core bit.

I have designed this core barrel and describe and illustrate it herein as used by me in oil well drilling, although it is equally applicable in all instances where a core for geological study is called for.

I have sought by my method of construction to avoid friction of the core as it passes upward into the core barrel. This I accomplish by providing a degree of lubrication within the core bit by means of spiral grooves in the inner surface thereof; and also by having the bore of the core barrel slightly greater in diameter than that of the core bit proper.

Another valuable feature of my tool is found in the fact that I have designed the points of the drill bits to project slightly below the tips of the core bit teeth, in order that said drill bits may make the first advance into the virgin formation, while having their projecting cutting ends taper inwardly and upwardly to the outer surface of the core bit so that the formation immediately surrounding the core bit may not be "chewed" or disturbed in any manner by any part of the tool except the core bit itself, thus tending to insure a perfect core.

Referring more particularly to the drawings:

1 indicates a cylindrical core barrel, divided longitudinally into practically identical halves, 1^a—1^b, and provided with a driving head and a drilling head of diameters larger than that of the long shaft of the cylinder or barrel.

2 indicates the beveled and threaded driving end of the barrel adapted to receive a driving head 12.

3—3 indicate interlocking longitudinal projections and corresponding recesses in halves 1^a—1^b, adapted to accurately align said halves.

4 indicates a beveled and threaded section of barrel 1 adapted to receive internally 70 threaded sleeve 8.

5—5 indicate recesses in the body of halves 1^a—1^b adapted to form housings for bolts 9—9.

6—6 indicate an annular groove in the upper shoulder of the driving head 1^c of barrel 1, adapted to correspond with a similar groove in the lower abutting end of drive-head 12 to afford free circulation for fluids in the well should holes 7—7 in said barrel and said drive-head fail to fall in exact alignment.

7—7 indicate multiple longitudinal holes throughout the length of barrel halves 1^a—1^b and head 12, adapted to provide circulation for fluids in the well as the drill advances.

8 indicates a sleeve surrounding barrel 1, removable over the driving end of the same, and provided with internal beveled thread 8^a to receive beveled thread 4.

9—9 indicate removable bolts adapted to hold halves 1^a—1^b in exact apposition.

10—10 indicate drill bits set in corresponding key sockets in the drilling head of halves 1^a—1^b.

10^a—10^a indicate the points of drill bits 10—10.

11—11 indicate a core drill or shoe, provided with the usual cutting or drilling teeth, lugs 11^a adapted to enter corresponding recesses on the inner surfaces of the drill-head of barrel, and provided further with spiral grooves on the inner surface thereof, 13—13.

12 indicates a driving head adapted to screw onto beveled thread 2 of barrel 1 by

means of internal beveled thread 12^a; provided with outside thread 12^b for attachment of a drill shaft; provided also with perforations, 7—7, therethrough for circulation of fluid, and with a cylindrical end, 12^c, of smaller diameter adapted to contain a ball valve, 12^b, of the ordinary type.

14—14 indicate corresponding and opposing key sockets in halves 1^a—1^b, adapted to 10 receive corresponding keys to hold said barrel halves in fixed apposition.

Assembling of the core barrel comprises: core bits 11—11 are placed within halves 1^a—1^b, lugs 11^a—11^a serving for correct placement and to prevent core bit 11 from turning in the barrel 1; halves 1^a—1^b are brought together; bolts 9—9 are placed and tightened; sleeve 8 is passed over the driving end of barrel 1 and screwed down tightly against 20 the projecting shoulder at the base of thread 4; keys corresponding to key-sockets 14—14 are driven in; driving head 12 is screwed onto thread 2 and attached to a driving shaft by means of thread 12^b. Drill bits 10—10 25 are then driven into corresponding sockets in the drill-end of barrel 1, the upper end of the said bits being prevented from passing upward by sleeve 8.

The tool is then ready for entering the 30 hole and proceeding to drill and cut a core.

It is important to note that drill points 10^a—10^a of drill bits 10—10 project downward slightly beyond the points of the teeth of core bit 11, and are therefore the first to 35 enter the earth formation. And to note further, that the cutting edges of bits 10—10 taper inwardly at an angle of approximately 45%, to core bit 11, with the result that core bit 11 will advance some distance into new 40 and solid formation before said drill bits 10—10 have disturbed the formation immediately surrounding the core bit 11.

As the tool advances into the earth formation, circulation of the water and débris within 45 in the hole must be maintained after the advancement of the tool has closed circulation both within and without the core barrel. Therefore I have provided multiple perforations 7—7 which allow the fluid to pass upward to the comparatively open hole above 50 the tool.

After the barrel has advanced the desired distance into the earth formation, that is, when the core barrel has advanced its full 55 length, the tool is removed from the hole and the process of assembling above set forth is reversed to free the core. The core will then be found in one continuous piece, showing the exact strata through which the barrel 60 has advanced. In actual use in oil fields the core barrel is made of varying lengths and diameters as need requires.

Advancement of the core through core bit 11 is made easier because of spiral groove 65 13—13 on the inner surface thereof. It will

be noted that the diameter of the core bore in the barrel 1 is slightly greater than that of the core bit 11. The body 1 forms a core retainer tube and a drill shank for the cutters. A threaded pin 2 is provided for attachment to the drill pipe or string. This structure is simple, strong, and easily manipulated in taking and capturing cores and in their removal from the barrel for examination.

Having thus described the construction and operation of my invention as applied in one field of industry, I claim as new and desire to obtain Letters Patent of the United States upon:

1. A core barrel of the character disclosed comprising separable halves and means for locking said halves in rigid apposition; a drive head adapted to screw onto the driving head of said barrel by means of beveled threaded section therein; the drill-head of said barrel being provided with a counterbore adapted to receive a core bit, and multiple key sockets in the periphery thereof adapted to receive drill bits; said drill bits being tapered from drill point inward and upward and abutting upon said core bit; the points of said drill bits projecting beyond the said core bit.

2. A core barrel of the character disclosed comprising longitudinal separable halves and means for rigidly fastening said halves to form a cylindrical chamber within; the driving end of said barrel being provided with a shoulder against which a driving shaft abuts; the drill end of said barrel being circumferentially larger than said barrel shaft; a section of said barrel having an upwardly tapered thread adapted to receive a removable sleeve provided with a corresponding internal tapered thread; said enlarged drill end being provided with a counterbore in the end thereof adapted to receive a core bit; said drill end being further provided with multiple key sockets longitudinally cut in the periphery thereof and adapted to receive multiple drill bits; multiple drill bits adapted to fit tightly into said key-sockets and formed to project beyond the periphery of said drill head to serve as reamers; said drill bits being tapered upward and inward from the external points thereof and abutting against said core bit; and a core bit having an internal diameter slightly smaller than the bore of said barrel, and being provided with a spiral groove on the inner surface thereof.

3. A core barrel of the character disclosed comprising separable longitudinal halves and means for rigidly holding said halves to form a cylindrical barrel; the driving end of said barrel being provided with a tapered thread adapted to receive a driving shaft; both ends of said barrel being larger circumferentially than the middle section; an

annular groove in the upper shoulder of said enlarged driving end; perforations opening into said groove and passing longitudinally through said barrel; said barrel being provided with a threaded tapered section immediately above the enlarged drilling end; a removable sleeve adapted to screw onto said threaded section and abut against the upper shoulder formed by said enlarged barrel

10 end; said drilling end being provided with corresponding longitudinal key-sockets in said halves, adapted to receive corresponding keys to hold said halves rigidly in apposition.

15 4. A rotary core barrel tool of the character described comprising an outer shell extending substantially the full length of the core receiving bore and forming a core retainer, said shell being divided longitudinally throughout the length of said bore into a plurality of sections whereby it may be opened to expose and release an entire core, cutters at the bottom of said tool and means to lock the sections of said shell in rigid apposition.

20 5. A rotary core barrel tool of the character described comprising a shell extending substantially the full length of the core receiving bore and including all of the core receiving bore, said shell being split longitudinally into a plurality of sections whereby it may be opened to expose and release an entire core, cutters at the bottom of said shell, said shell serving as a shank for said cutters, and means to lock the sections of said shell in rigid apposition.

25 6. A rotary core barrel tool of the character described comprising a shell extending substantially the full length of the core receiving bore of the tool forming a core retainer and having a coupling member at the top for securing it to a drill string

whereby it may be rotated, cutters at the bottom of said shell, the latter serving as a shank for said cutters, said shell being split longitudinally the full length of the core receiving bore whereby it may be opened to expose and release an entire core, and means to lock the sections of said shell in rigid apposition. 45

7. A rotary core barrel tool of the character described comprising a shell extending substantially the full length of the core receiving bore of the tool forming a core retainer and having a coupling member at the top for securing it to a drill string whereby it may be rotated, cutters at the bottom of said shell, the shell serving as a shank for said cutters, said shell being split longitudinally the full length of the core receiving bore whereby it may be opened to expose and release an entire core, and a tubular lock member for encompassing said shell and locking the sections thereof in rigid apposition. 50 60

8. A rotary core barrel tool of the character described comprising a shell extending substantially the full length of the core receiving bore of the tool forming a core retainer and having a coupling member at the top for securing it to a drill string whereby it may be rotated, cutters at the bottom of said shell, the shell serving as a shank for said cutters, said shell being split longitudinally the full length of the core receiving bore whereby it may be opened to expose and release an entire core, and a lock collar removably screwed on said shell for holding the sections thereof assembled. 70 75

In testimony whereof, I have signed my name to this application and power of attorney. 80
